PULP MOLDING DIE

Harold S. Crane, Palmer, Mass., assignor to Diamond Gardner Corporation, New York, N.Y., a corporation of Delaware

Application May 6, 1958, Serial No. 733,378

4 Claims. (Cl. 162—411)

This invention relates to pulp molding dies, and more particularly to foraminous dies for molding by suction deposition of pulp fibers thereon to produce pulp articles having localized areas of special configuration or design.

In the manufacture of molded pulp articles having intricately shaped or sharply curved and defined areas, considerable difficulty has been encountered heretofore in the construction of suitable molding dies. In general, two types of dies have been employed for this purpose, namely, the laminated die and the screen-covered die. The laminated type die is exemplified by Sheffield Patent 1,984,384 and a typical screen-covered die is disclosed in Chaplin et al. Patent 2,359,201. It has been recognized for many years that each of these types of dies possesses its own advantages and disadvantages, and various proposals have been made to provide an improved die structure.

Laminated dies are highly adaptable for forming well defined complex shapes, but they are usually undesirably heavy, and they are expensive to manufacture and to maintain for a sufficiently long useful life. On the other hand, the screen-covered type dies are relatively inexpensive, but they are less suitable for the formation of intricately shaped pulp articles, since it is extremely difficult to shape wire mesh into complex and sharply curved patterns without rupturing the wire or distorting the mesh to such an extent as to alter its drainage characteristics and create mechanical weaknesses therein. In order to avoid the difficulties characteristic of both types of dies, it has been proposed that a large die surface could be formed by clamping together a great many small individually screen-covered sections having the desired contour, and it has also been suggested that such small individually screen-covered sections could be bolted to the face of a large ordinary screen-covered die. However, none of the structures proposed heretofore have been completely satisfactory for the formation of sharply defined contrasting localized areas.

An object of the present invention is to provide a new and improved pulp molding die.

Another object of the invention is to provide a new and improved die structure for molding pulp articles having localized intricately shaped or sharply curved and defined areas.

Still another object of the invention is to provide a simplified, inexpensive composite die structure having localized areas designed to produce sharply defined zones of intricate contour, contrasting surface texture, or non-uniform thickness in pulp articles molded thereon.

Other objects and the nature and advantages of the instant invention will be apparent from the following detailed description, taken in conjunction with the accompanying drawings, wherein:

Fig. 1 is a plan elevation view of a pulp molding die embodying the invention;

Fig. 2 is an enlarged corresponding view of a portion of the die as shown in Fig. 1;

2

Fig. 3 is a vertical section taken along line 3—3 of Fig. 2; and

Fig. 4 is a perspective view of a portion of a molded pulp article produced on a die embodying the invention.

5 In accordance with the present invention, foraminous pulp molding dies of conventional screen-covered construction may be provided with specially designed localized areas for producing sharply defined zones of intricate contour, contrasting surface textures, or non-uniform thickness in pulp articles produced thereon, essentially by incorporating a relatively small specially designed laminated molding die insert into such conventional screen-covered dies. The laminated insert is suitably contoured to produce intricate shapes, or other contrasting effects, 15 as may be desired.

In order to demonstrate the principles of the invention, the molding die selected for illustration in Figs. 1, 2, and 3 is designed for the production of relatively shallow, generally rectangular molded pulp trays having 20 on each of the four sides thereof a relatively small decorated area. However, it should be understood that the invention may be employed advantageously in the manufacture of other molded pulp articles, such as egg trays, pie plates, flower pots, and the like, which may require 25 localized areas of sharply defined contrasting design.

As is best shown in Fig. 3, the illustrated molding die comprises an open-faced perforated forming plate 10 covering a suction chamber 12, formed in the interior of a generally rectangular die frame 14 having upstanding end walls 15, said plate having an exterior forming face 16 covered substantially all of the forming face of the plate 10. In the usual manner, the chamber 12 is adapted for connection to a suitable source of suction, 30 which causes pulp fibers to be deposited on the screen 16 when the molding die is immersed in a vat containing a thin liquid slurry of pulp fibers. The outer edges of the screen 16 are secured to the frame 14 by means of a retaining ring 18, which is removably fastened to the 35 tops of the walls 15 by a plurality of bolts 20. The inner portions of the screen 16 are contoured to fit snugly against the perforated forming plate 10, and due to the inherent stiffness of the wire mesh of which this screen is made, it retains this shape. Although the plate 10 40 in the illustrated embodiment of the invention is shown as a single undivided unit and the screen 16 covers this entire unit, it is contemplated that the forming plate 10 45 may be sub-divided into a plurality of individually screen-covered sections which may be clamped together to form 50 a unitary screen-covered die.

On each of the four sides of the molding die shown in Fig. 1, localized areas of contrasting design are formed by laminated inserts 22. In Fig. 4 there is shown a portion of a molded pulp tray 24 produced by the die illustrated in Figs. 1, 2 and 3, and as depicted in Fig. 4 the inserts 22 produce an ornamental projection 26 having three adjacent semicircular fluted sections 28. The sharply curved and intricately formed details of the fluted sections 28 of the projection 26 are clearly defined, and 55 they are in distinct contrast to the surrounding smooth portions of the surface of the tray 24 which were formed by the wire mesh screen 16.

The laminated inserts 22 are constructed from a plurality of flat lamina 30 assembled in compact side-by-side relationship, routed or otherwise cut back along one edge thereof to form a contoured molding face 32 on each insert 22, while the other edges thereof are smooth and even. The contoured molding faces 32 are designed to form the adjacent semicircular fluted sections 28 of the 60 projection 26 on the molded pulp tray 24. For this purpose, the molding faces 32 are mounted in substantial alignment with the forming face of the perforated form- 65 70

ing plate 10. Along each contoured face 32 alternate lamina 30 are cut back farther, as shown at 33 in Fig. 3 to provide drainage channels which communicate with the suction chamber 12 through a channel 34 formed in the plate 10. Thus, when the entire molding die is immersed in pulp slurry and suction is applied to the chamber 12, excess fluid is drained transversely through the cut back portions 33 of the lamina 30 and thence through the channel 34 and the chamber 12, thereby causing a layer of pulp fibers to be deposited onto the molding face 32 of the insert 22.

Preferably the inserts 22 are mounted in and project through the forming plate 10, and they are seated in and secured to the die frame 14. The end walls 15 of the die frame 14 are provided with a plurality of recesses 36 into which the laminated inserts 22 are adapted to fit snugly and be clamped therein by the retaining ring 18. The screen 16 preferably extends into and covers at least portions of the sides and bottom of the recesses 36. As a matter of convenience in illustrating the invention, the inserts 22 are shown mounted in recesses 36 formed only in the end walls 15 of the die frame 14. However, it is evident that inserts of this type may be mounted at any other selected location, such as any portion of the surface of the perforated forming plate 10 of the molding die, and in such event it may be desirable to provide enlarged drainage channels within the inserts 22 to insure adequate drainage into the suction chamber 12.

Molding dies embodying the invention possess all of the advantages of both the standard entirely laminated die and the standard screen-covered type die used heretofore, while eliminating the troublesome disadvantages inherent in said prior art dies. Composite dies constructed in accordance with the invention are particularly useful in the production of localized areas having attractive surface variations, sharply defined intricate designs, distinctly contrasting surface texture, and non-uniform thickness to provide regional ornamentation or strength.

It will be obvious to those skilled in the art that various changes may be made without departing from the spirit of the invention, and therefore the invention is not limited to what is shown in the drawings and described in the specification, but only as indicated in the appended claims.

What is claimed is:

1. A pulp molding die, comprising a die frame having an interior suction chamber adapted for connection to a source of suction, a perforated forming plate covering said chamber, said plate having an exterior forming face contoured to mold pulp articles, a wire mesh screen covering substantially all of the forming face of said plate, and a laminated molding die insert comprising a compact assembly of lamina mounted in a recess provided in the forming plate and having drainage channels communicating with the suction chamber, said insert having a molding face substantially aligned with the forming face of said plate and contoured to form sharply defined localized areas of contrasting design on the surface of pulp articles molded thereon.

2. A pulp molding die, comprising a die frame having an interior suction chamber adapted for connection to a source of suction, a perforated forming plate covering

5 said chamber, said plate having an exterior forming face contoured to mold pulp articles, a wire mesh screen covering substantially all of the forming face of said plate, and a laminated molding die insert comprising a plurality of lamina assembled in compact side-by-side relationship mounted in a recess formed in the die frame and projecting through the forming plate, said insert having a contoured molding face substantially aligned with the forming face of said plate and having drainage channels communicating with the suction chamber, said molding face being contoured to form sharply defined localized areas of contrasting design on the surface of pulp articles molded thereon.

3. A pulp molding die, comprising a die frame having upstanding end walls and having an interior suction chamber adapted for connection to a source of suction, a perforated forming plate covering said chamber, said plate having an exterior forming face contoured to mold pulp articles, a wire mesh screen covering substantially all of the forming face of said plate, a retaining ring mounted on said end walls for clamping the outer edges of the screen thereto, and a laminated molding die insert comprising a plurality of lamina assembled in compact side-by-side relationship mounted in a recess formed in said end walls and secured therein by the retaining ring, said insert projecting through the forming plate and having a contoured molding face substantially aligned with the forming face of said plate, alternate lamina being provided with drainage channels communicating with the suction chamber, said molding face being contoured to form sharply defined localized areas of contrasting design on the surface of pulp articles molded thereon.

4. A pulp molding die, comprising a die frame having upstanding end walls and having an interior suction chamber adapted for connection to a source of suction, a perforated forming plate covering said chamber, said plate having an exterior forming face contoured to mold pulp articles, a wire mesh screen covering substantially all of the forming face of said plate, a retaining ring mounted on the tops of said end walls for clamping the outer edges of the screen thereto, and a laminated molding die insert comprising a plurality of flat lamina assembled in compact side-by-side relationship mounted in a recess formed in said end walls and secured therein by the retaining ring, said screen extending into and covering at least portions of the walls of said recess, said insert projecting through the forming plate and having a contoured molding face substantially aligned with the forming face of said plate, alternate lamina being cut back below the molding face to form drainage channels communicating through the perforated forming plate with the suction chamber, said molding face being contoured to form sharply defined localized areas contrasting in design with the areas formed by the screen on the surface of pulp articles molded thereon.
